UNITED STATES PATENT OFFICE.

EMIL CHALUPA, OF NEW YORK, N. Y.

DESIGN FOR A FURNITURE-CASTER.

56,583.

Specification for Design.

Patented Nov. 16, 1920.

Application filed April 3, 1920. Serial No. 371,166. Term of patent 14 years.

To all whom it may concern:

Be it known that I, EMIL CHALUPA, a citizen of the United States, residing at New York, New York county, and New York State, have invented a new, original, and ornamental Design for Furniture-Casters, of which the following is a specification, reference being had to the accompanying drawings, forming a part thereof, and in which—

Fig. 2 is a vertical sectional view through the cup of the same.

Fig. 3 is a plan view of the caster.
What I claim is:

The ornamental design for a furniture caster, as shown.

In testimony whereof I have signed my name to this specification in the presence of two subscribing witnesses, this 23d day of March, 1920.

EMIL CHALUPA.
